GRINDING MILL

William A. Weidlich, East Bound Brook, N. J.

Application April 27, 1937, Serial No. 139,181

1 Claim. (Cl. 83—22)

This invention relates to mills adapted for grinding paints, varnish, lacquer, pigment, ink or similar substances.

The object is to provide simplified and effective means for grinding a substance, such for example, as a pigment, and a vehicle, such as a suitable oil. The said substance serving as a lubricant between the surface of the roll and the coating surface of the shoe, between which surfaces the fit is extremely close, whereby the material may be reduced by a single pass through the mill to a condition of extreme fineness.

The invention comprises a single roll, surmounted by a semi-circular shoe, fitting closely the upper half of the periphery of the roll.

The invention also comprises means for resiliently adjusting the fit or distance between roll and shoe.

The invention also comprises improved regulatable means for feeding the material to the mill, and adjustable means for regulating the rate of feed, and also mechanical means for cooperating in introducing the material between the roll and shoe.

25 The invention also comprises improved details in construction and operation.

Referring to the drawing which illustrates merely by way of example suitable means for effecting the invention:

30 Fig. 1 is a section on line 1—1 of Fig. 2.

Fig. 2 is a section on line 2—2 of Fig. 1.

Fig. 3 is a view similar to Fig. 1, showing a modification.

Fig. 4 is an elevation, on a reduced scale, showing the assembly.

Similar numerals refer to similar parts throughout the several views.

Referring to Figs. 1 and 2. The roller 10 is mounted on a horizontal shaft 11 running in suitable bearings 12 supported by a base 13. Surmounting the upper half of roller 10 is the friction shoe 14 having end flanges 15 secured to the base 13 by bolts or studs 16 and the nuts 17. Helical springs 18 are mounted on the studs and interposed between the flanges 15 and the nuts 17, so that an adjustable resilient pressure may be exerted upon the friction shoe at four points which resilient pressure is adapted to cooperate with the gravity pressure of the shoe upon the upper peripheral surface of the roll. The shoe 14 is also provided with lateral arcuate flanges 19 overlapping the outer side margins of the roller, near its periphery. The shaft of roller 10 is provided with a suitable drive pulley 20. 55 Both roller and shoe are made hollow with suit-

able inlets and outlets 21 and 22 for a temperature controlling fluid.

A passage of chamber 23 is provided in or through said shoe 14, having a nozzle 24 extending outwardly from said shoe for connection with a material supply pipe 25. The passage 23 extends laterally approximately the width of the shoe and provides a delivery mouth open to the roller 10, and flares upwardly in the direction of rotation of the roller. 10

Near the diametrically opposite side of the roller 10, from the point or line of delivery thereto of the material, a suitable scraper 26 is provided for scraping the paste-like material carried on the face of the roller, from said face 15 as it leaves the shoe.

In order to secure a very close smooth fit between the peripheral surface of the roller 10 and the cooperating face or surface of the shoe 14, the said surfaces are ground together very 20 smooth and to perfect fit, as by rotating the roller in the shoe with a suitable abrasive, such as emery in oil.

In operation—The shoe is adapted to be held in proper position, with respect to the roller, 25 by means of the nuts 17 on studs 16, operating upon the springs 18. There are two such studs on each end of the shoe. The stud receiving holes 27 in flange 15, which is on the far side of the shoe, that is the end remote from the 30 intake chamber or passage 23, are sufficiently large to permit slight play on the studs.

The adjustment is made to suit the character of material to be treated, and the degree of fineness desired. 35

In such adjustment, the coating surface of the shoe is usually spaced very slightly from the peripheral surface of the roller, adjacent the end of the shoe which contains the delivery passage 23. There is a gradually increasing closeness 40 of fit between roller and shoe toward the far end of the shoe, which is adjacent the scraper 26.

As the roller revolves while the shoe is held stationary, the friction between roller and shoe causes a very effective and fine grinding of the 45 material which is carried by the roller around the shoe, while, at the same time, the material acts as a lubricant to prevent injurious friction between roller and shoe.

The mere weight of the shoe would normally 50 cause a close preliminary engagement between shoe and roller, while the chief function of the resilient adjustment is to oppose the separating movement of shoe from roller due to the introduction of material therebetween.

- In case at any time an undue amount of material should be carried between the roller and shoe, or in case the material should be unduly hard or lumpy, the springs will yield slightly to prevent damage to the apparatus, while at the same time the crushing and grinding pressure is materially increased.
- The material is delivered into chamber 23 from any suitable source of supply, such as a tank 28, either by gravity or by pressure above atmosphere. The rate of the supply may be regulated by various regulating means, for example the hand valve 29, or the desired rate of supply or pressure may be created by pumping air into a closed supply tank, or by pumping of the material to chamber 23 by a variable delivery pump, such as 30. It may also be desirable to stir the material in the tank to facilitate an even or uniform form delivery. In such case the usual mixing device, such as 31, may be provided in the tank. The shoe 14 is provided with the flanking flanges 19, extending a short distance over the sides of roller 10, to prevent material from discharging laterally from between roller and shoe.
- The roller is rotated by any suitable prime mover, such as a variable speed motor 32, at any desired speed, for example 440 R. P. M., and of course the rate of supply and the roller speed are relatively adjustable.
- The material to be ground passes between the roller 10 and shoe 14 for approximately one-half the circumference of the roller, which causes the pigment particles to be rubbed between the two surfaces under pressure; preferably under a yielding pressure.

I have found that a travel of $4\frac{1}{2}$ inches between the roller and the shoe was sufficient grind for a mixture of T.02 in blown castor oil and Lindol to produce lacquers extremely high in glaze and free from objectionable agglomerates.

It will be noted that the larger the diameter of the roller, the more efficient the grind. For example, a roller 8 inches in diameter, fitted with a shoe one-half the circumference of the roller, would have approximately 12 inches of actual grind. Whereas a roller 20 inches in diameter, would have approximately 30 inches of grinding contact.

In Fig. 3, I show a modification of the device, adapted especially for the grinding of harsh pigments, in which an auxiliary or crushing roller is employed.

This crushing roller 33 is mounted in the upper part of chamber or passage 23, of the shoe 14, with its periphery close to or engaging the periphery of roller 10. As this roller is mounted in the shoe 14, it is automatically adjusted, in relation to the periphery of roller 10, with the adjustment of the shoe. It may obviously be adjusted in other ways. If this roller 33 is rotated to run at the same R. P. M. as roller 10, in view of the difference in diameters, it will produce a differential shearing action, which will tend to crush the harder agglomerates of the pigment to a uniform size. The desired ratio between the peripheral speeds of the two rollers may be secured by suitable gearing, such as 34 and 35.

The pump 30, shown in Fig. 4, is marked with the letters PVD, indicating variable delivery pump, so described in column 1 lines 16 and 17 of page 2, and the motor 32, in Fig. 4, is marked with the letters MVS, indicating variable speed motor, so described in column 1 line 26 of page 2.

What I claim is:

In a device of the character described for grinding pigments and similar substances in a fluid vehicle, and especially adapted to eliminate objectionable agglomerates, the combination of a roller mounted to rotate on a horizontal axis, a shoe having a face co-acting with the peripheral surface of the roller which is above the horizontal plane of its axis, said shoe having a limited automatic up-and-down movement during the operation of the device, said roller and shoe being provided with ground-together co-acting surfaces, secured by rotating the roller within the shoe with a suitable abradant, a chamber formed within the shoe, a crushing roller mounted therein and partaking of the said up-and-down movement, and means for delivering material between the peripheral surfaces of the two rollers located adjacent its entrance beneath the shoe, and in the direction of rotation of the two rollers.
